DESIGN FOR A DARNER

David F. Ellis, Clintonville, Wis.

Application February 12, 1945, Serial No. 117,896

Term of patent 14 years

(Cl. D3—19)

To all whom it may concern:

Be it known that I, David F. Ellis, a citizen of the United States, residing at Clintonville, in the county of Waupaca and State of Wisconsin, have invented a new, original, and ornamental Design for a Darner, of which the following is a specification, reference being had to the accompanying drawing, forming part thereof.

Figure 1 is a side elevational view of a darner, showing my new design,
Figure 2 is a rear elevational view, and
Figure 3 is a front elevational view thereof.

I claim:

The ornamental design for a darner as shown.

DAVID F. ELLIS.
